UNITED STATES PATENT OFFICE

ARTHUR F. PYM, OF SWAMPSOFT, MASSACHUSETTS, ASSIGNOR TO UNITED SHOE MACHINERY CORPORATION, OF PATERSON, NEW JERSEY, A CORPORATION OF NEW JERSEY

LASTING MACHINE

Application filed March 17, 1926, Serial No. 95,280. Renewed July 3, 1928.

This invention relates to lasting machines, and is herein illustrated in its application to means for lasting the toes of shoes, although it is to be understood that in its more general aspects the invention is not limited to toe-lasting means.

An object of the invention is to provide power-operated means for performing end-lasting operations under such control as to enable the operator, by the use of the machine, to accomplish in a speedy and effective manner results best suited to the character of the work in hand. In the use of a power-operated toe-lasting machine it is an advantage for the operator to be able to stop the machine at will in the course of its operations on the shoe, or during a portion at least of the cycle of operations, so as to afford an opportunity for manual pulling or arranging of the upper materials when such manipulation appears to be necessary. It is also an advantage for the machine to come to a stop automatically at a point in the cycle where stopping of the machine is required in operating on each shoe, for example when the wipers are in position for a binder wire to be applied about the toe, so as to relieve the operator of the care and attention required in order to stop the machine each time with the wipers in exactly the right position. The present invention provides an organization that combines both these advantages. The construction herein shown comprises controlling mechanism of such a character that by release of a starting treadle, which he would otherwise hold depressed, the operator may bring the machine to a stop at any point in its cycle, including also means for bringing the machine to a stop automatically at a predetermined point in the cycle if the treadle is not released. Under some conditions it may be desirable to eliminate this automatic stop; as, for example, in case it is desired to repeat the cycle of operations on a shoe, or where it may be practicable for the operator to draw the binder wire about the toe without stopping the machine for that purpose. The invention accordingly further provides a construction such as to enable the operator, if desired, to cause the machine to run past the point where

it would normally be brought to a stop, this result being accomplished in the construction shown by depression of the treadle farther than when it is desired that the automatic stopping means shall function.

In accordance with a further feature of the invention there is provided means adapted to be utilized, when the machine has been brought to a stop, to impart to the wipers retractive movement of sufficient extent to facilitate manual pulling or adjusting of portions of the upper materials engaged by the wipers. It may, for example, be sometimes desirable thus to manipulate the upper at that point in the cycle when the wipers are just beginning to wipe the upper inwardly from the edge of the insole; and in order that this may be readily done, the machine herein shown is provided with a hand lever connected to the wiper-operating mechanism for backing off the wipers while the power driving means is at rest, the connections between the wipers and the driving means including a yielding element which permits the manual retractive movement of the wipers to be effected.

The above and other features of the invention, including certain novel details of construction and combinations of parts, will now be more particularly described by reference to the accompanying drawings and pointed out in the claims.

In the drawings,

Fig. 1 is a view in front elevation of a toe-lasting machine in which the invention is embodied;

Fig. 2 is a plan view of the lower left-hand portion of the machine shown in Fig. 1; and

Fig. 3 is a view partly in left-hand end elevation and partly in section on the line III-III of Fig. 1.

To support or position the shoe for the toe-lasting operation, any suitable means may be utilized, the construction shown comprising mechanism which is substantially like that fully illustrated and described in Letters Patent No. 1,693,119, granted upon my application on November 27, 1928, and which, therefore, need not be described herein in

detail. Briefly stated, this mechanism comprises a vertically movable toe rest 4 yieldingly supported by a spring 6 and arranged to be locked by means not herein shown to 5 sustain the shoe rigidly against downward pressure of the lasting means thereon. Co-operating with the toe rest 4 is a hold-down arm 8 provided with pins 10 adapted to project through holes in the insole of the shoe 10 into holes formed in the bottom of the last to position the last in proper relation to the lasting mechanism, as more fully described and claimed in Letters Patent No. 1,674,060, granted upon my application on June 19, 15 1928. The arm 8 is mounted on a vertically movable plunger 12 which is moved downwardly to a definite point to clamp the shoe upon the toe rest 4 by power-operated means including a clutch 14, one member of which 20 is connected to a continuously running shaft 16. The clutch 14 is controlled independently of the lasting mechanism by means of a treadle 18. When the treadle is depressed, the shoe which has already been mounted 25 upon the pins 10 is clamped upon the toe rest 4 in proper position for the lasting operation, whereupon the shoe-positioning mechanism comes to rest and holds the shoe until the treadle 18 is again depressed to cause the 30 release of the shoe after the lasting operation has been completed.

The lasting mechanism herein shown is also, in many respects, substantially like that fully described in Letters Patent No. 35 1,693,119. This mechanism comprises toe-embracing wipers 20 supported upon a wiper carrier 22 which is pivotally supported at its rear end by means of trunnions 24 upon the forked upper end of a lever 26 pivoted at 28 40 on the frame of the machine. Near its other end the wiper carrier 22 is pivotally supported upon a rod 30 which is connected by a coupling member 32 and spring means hereinafter described to a rod 34 connected at its 45 lower end to a lever arm 36 fast on a rock shaft 38. Also fast on the rock shaft 38 is a lever arm 40 provided with a roll 42 engaged by a path cam of suitable contour formed in one side of a cam wheel 44 which 50 is fast on a power-operated shaft 46. By this mechanism upward movement is imparted to the wiper carrier 22 to cause the wipers 20 to upwipe the upper to the edge of the insole, and also downward movement 55 to increase the pressure of the wipers upon the upper in wiping it inwardly over the insole.

Advancing movement of the wipers 20 lengthwise of the shoe results from bodily 60 forward movement of the wiper carrier 22 in response to the action of the lever 26. Connected to the lever 26 is an arm 48 which is yieldingly connected by a rod 50, a coupling member 52 and a spring 53 to a lever arm 54 fast on a rock shaft 56. Also fast 65

on the shaft 56 is a lever arm 58 provided with a roll 60 engaged by a suitably shaped path cam formed in one side of the cam wheel 44. By this mechanism forward movement is imparted to the wiper carrier 22 in time relation to the upward and downward movements of the carrier hereinabove described, and by the same mechanism also closing movement is imparted to the wipers 20 through the operation of a plunger 62 and connections more fully shown and described in Letters Patent No. 1,693,119. For the latter purpose the lever 26 is connected by a link 64 to a lever 66 which is pivoted at 68 on the frame of the machine, the lever 66 being connected by links 70 to a member 72 through which the plunger 62 is operated.

It will be understood that by the operation of the power-driven means above described movements are imparted to the wipers 20 in a predetermined cycle to cause them to advance and close about the toe and then to upwipe the upper to the edge of the insole, and thereafter further to advance and close to wipe the upper inwardly over the bottom of the insole while bringing increased downward pressure to bear upon the upper; and also to cause them thereafter to withdraw from the shoe and return to starting position. In the advancing and closing movements of the wipers the spring 53, which bears at its upper end against the coupling member 52 and at its lower end against a collar 74 fast on the rod 50, affords provision for yield, so that the edges of the wipers are pressed yieldingly against the end and sides of the toe in the upwiping operation and are also yieldingly engaged with the upper in wiping it inwardly over the bottom of the insole. The rod 50 extends downwardly through a bearing 76 in the coupling member 52, and at its lower end carries nuts 78 which are normally spaced below the bearing 76, as illustrated, but are arranged to be engaged by the bearing after a certain amount of yield of the spring 53. This arrangement is provided in order to render positive the final application of inward wiping pressure to the upper on welt shoe work, so as to ensure that the upper will be creased properly in the angle between the feather and the rib of the insole to receive the toe binder wire.

In the connections for imparting downward movement to the wiper carrier, to cause the wipers to press firmly down upon the upper in wiping it inwardly over the bottom of the insole, there is also provision for yield. It will be seen that the coupling member 32 bears upwardly against a nut 80 on the rod 30 to transmit movement positively to the wiper carrier in the upwiping operation. Within the coupling member 32 are a light spring 82 and a heavier spring 84, both of which bear at their upper end against the coupling member, the spring 82 being seated at its lower end

upon a collar 86 which is fast on the rod 30, and the spring 84 bearing at its lower end upon the enlarged head of a thimble 88, the lower portion of which is slidably mounted 5 in an opening in the coupling member 32. The rod 30 extends downwardly through the thimble 88 and is provided with nuts 90 which are normally spaced below the lower end of the thimble. It will thus be seen that when 10 sufficient resistance to downward movement of the wipers against the shoe is encountered, the light spring 82 will first yield until the coupling member 32 moves downwardly along the rod 30 far enough for the lower end of the thimble 88 to engage one of the nuts 90 15 on the rod. Thereafter further downward movement of the member 32 relatively to the rod 30 results in compression of both the springs 82 and 84, so that the downward pressure 20 of the wipers upon the shoe is considerably increased. The parts are so timed in their operation that compression of the light spring 82 alone takes place during the inward movement of the wipers over the margin 25 of the insole, the heavier spring 84 coming into play in response to further downward movement of the rod 34 substantially at the end of this overwiping movement, at the time when the inwardly directed pressure 30 of the wipers becomes positive, as hereinbefore explained. In this way the upper materials are subjected to heavy downward pressure at the end of the overwiping operation, in preparation for the application of the toe 35 binder to the shoe. The mechanism which thus affords provision for yield in the downward pressure applying movement of the wipers is substantially the same as that described and claimed in Letters Patent No. 40 1,678,873, granted upon my application on July 31, 1928.

For operating the cam shaft 46 there is fast on the shaft a gear wheel 92 engaged by a worm 94 which is loosely mounted on the 45 power shaft 16, and connected to the worm by a coupling 96; is a cone clutch member 98 which is arranged to co-operate with a clutch member 100 fast on the continuously running shaft 16. The clutch member 98 is loosely 50 mounted on the shaft 16, and the coupling 96 is so formed as to permit this member to be moved along the shaft toward and from the clutch member 100 while maintaining a continuous operative connection with the worm 55 94. The clutch member 98 is controlled by a yoke formed on the upper end of a clutch-controlling member or lever 102 which is mounted for swinging movement about a shaft 104. A spring 106 connected to the 60 lever 102 tends to hold the clutch member 98 out of engagement with the member 100.

The clutch-controlling mechanism provided for purposes of this invention further includes a lever 108 which is mounted to swing 65 on the shaft 104 and is provided with a roll-

110 in engagement with a cam disk 112 which is fast on the shaft 46, one arm of the lever being engaged by a spring 114 to hold the roll 110 continuously in engagement with the disk 112. By reference to Fig. 2 it will be seen 70 that the other arm of the lever 108 is shaped to provide opposite side portions which are spaced from each other, and on the outer end of this arm there is pivotally mounted at 116 a downwardly curved lever or arm 118 on the free end of which there is secured a pin 120. Pivotally mounted on the arm 118 between its opposite ends is the head 122 of a rod 124 which projects upwardly through the space between the opposite side portions of 75 the lever 108 and carries a spring 126. Upon this rod is slidably mounted a block 128 having in one side a recess to receive the end of an arm 130 integral with the clutch-controlling lever 102. The spring 126 is confined between the block 128 and nuts 132 on the upper end of the rod 124. The pin 120 on the end of the arm 118 is engaged on its upper face by an arm 134 fast on a rock shaft 136 to which is secured a treadle 138. The treadle 80 85 is provided with a laterally projecting lug 140 arranged to engage a spring plunger 142 which is compressible in response to depression of the treadle. On the cam disk 112 there is provided a stop cam 143 for engaging the roll 90 95 110 to stop the machine at the end of the cycle, and an additional stop cam 144 which is operable, under conditions hereinafter explained, to stop the machine at a definite point before it reaches the end of the cycle, 100 for example, at the point where the wipers are in position for the toe binder wire to be applied to the shoe.

When the parts of the machine are in idle or starting position, as illustrated in Fig. 1, 105 the right-hand end of the lever 108 is depressed by the cam 143, the clutch member 98 is held out of engagement with the member 100 by the spring 106, and the arm 130 serves, through its connections to the curved arm 118, to support the pin 120 in a position such that the lug 140 on the treadle 138 is substantially in engagement with the plunger 142 without depression of the plunger from its normal position. It will be understood that 110 through the arm 134 the pin 120 supports the treadle, and that the pin is supported in turn by the arm 130 through connections including the spring 126 which is of such strength as not to be compressed by the weight of 115 the treadle.

When it is desired to start the operation of the lasting mechanism, after the clamping of the shoe in the manner explained, the operator depresses the treadle 138 and thereby 120 swings the arm 118 downwardly about its fulcrum 116 on the lever 108. In this downward swinging movement the arm 118 acts, through the rod 124 and the spring 126, on the block 128 to swing the arm 130 also down- 125 130

wardly and thereby to swing the lever 102 to the left and move the clutch member 98 against the resistance of the spring 106 into engagement with the member 100. The 5 spring 126 is preferably of such strength that it will yield only in response to further depression of the treadle after the member 98 has thus engaged the member 100. Immediately upon the starting of the machine the 10 cam 143 moves out of engagement with the roll 110, thus permitting a short upward movement of the right-hand end of the lever 108 in response to the action of the spring 114. In this movement of the lever 108 its 15 left-hand end which supports the arm 118 is lowered, and if the treadle is at this time held stationary by the operator, the arm 118 is swung downwardly about the axis of the pin 120 which serves as a fulcrum in engagement 20 with the arm 134. In this manner the rod 124 is moved farther downwardly than it was in response to the action of the treadle, with resulting compression of the spring 126. If now the operator should desire to bring 25 the machine to a stop at any point, for example with the wipers in position to begin the over-wiping operation, he may do so simply by releasing the treadle, thus permitting the spring 106 to act on the lever 102 to release 30 the clutch. It will be understood that, in this event, the treadle will be raised to a higher position than it occupied prior to the starting of the machine, by reason of the change in the position of the lever 108 where- 35 by the right-hand end of the arm 118, which carries the treadle-supporting pin 120, tends to occupy a higher position than it occupied at the start.

If the operator does not desire to bring 40 the machine to a stop until the wipers arrive, for example, in position for the toe binder wire to be applied to the shoe, he continues the pressure on the treadle, thereby holding the clutch member 98 in engagement with 45 the member 100. It is desirable that the operator be relieved of the necessity of releasing the treadle at exactly the right time for the wipers to stop in wiring position, in view of the difficulty of thus determining 50 the correct stopping point, and for the purpose of stopping the machine at this particular point in the cycle the cam 144 is accordingly provided. It will be evident, however, that if the operator continues to 55 hold the treadle depressed as low as the point to which it was necessary to move it in starting the machine, the cam 144 will be ineffective to accomplish the desired result, since it is no higher than the cam 143 which 60 was acting on the lever 108 at the time when the machine was started. In order, therefore, to permit the machine to be brought automatically to a stop at the desired point, the operator permits the treadle to be moved 65 upwardly by the plunger 142 and by the action

of the spring 126 on the arm 118 until the space between the block 128 and the head 122 of the rod 124, which resulted from previous compression of the spring 126, is substantially taken up. When the cam 144, 70 under these conditions, engages the roll 110 and thereby lifts the left-hand end of the lever 108, the arm 118 is swung upwardly about the axis of the pin 120 which again fulcrums on the arm 134, and thereby the block 128 is forced upwardly far enough 75 to cause the clutch member 98 to be moved out of engagement with the member 100. The spring plunger 142 serves as a convenient indication to the operator of the position 80 that the treadle should occupy in order to permit the automatic stopping of the machine in the manner described, the proper position of the treadle for that purpose being that in which the lug 140 is in engagement with the upper end of the plunger 142 without depression of the plunger. After 85 the wiring of the toe the operator again starts the machine in the same manner as in the first instance, and then again permits the treadle to be moved upwardly to that point 90 where the cam 143 can act to bring the machine to a stop at the end of the cycle. By the provision of this cam the operator is relieved of the necessity of exercising any 95 special care in order to bring the machine to a stop at exactly the right point for the presentation of another shoe.

From the above description it will be seen 100 that with the treadle depressed to a point which the operator may readily determine by the resistance of the plunger 142, the machine will be brought to a stop automatically 105 at a definite point prior to the completion of its cycle of operations, and again with 110 the parts of the machine in starting position, and further that irrespective of this automatic control the machine may be brought to a stop at any time at the will of the operator by releasing the treadle. This affords very 115 effective control of the operation of the machine, since it permits the operator to manipulate the upper materials at any point in the cycle where conditions indicate that such manipulation is desirable, while at the same time the operator is relieved of the necessity of exercising any special care to stop the machine at a definite point where it should be stopped in the operation on every shoe. If, as may be practicable under some 120 conditions, it is desired that the automatic stop before the end of the cycle be omitted, the operator holds the treadle 138 depressed far enough to render the cam 144 ineffective 125 to release the clutch. It will be understood that under these conditions, while the cam will operate on the lever 108 when it arrives in position to engage the roll 110, the arm 118 will not be lifted far enough thereby to relieve the compression of the spring 126 130

sufficiently to permit the release of the clutch. The machine may thus be made to run through its entire cycle uninterruptedly, while it may be brought to a stop at any point by releasing the treadle, as above explained. If desired also the machine may in this manner be made to repeat its cycle on the same shoe, without stopping at the point where the cam 143 would normally stop it.

10 It may be desirable under some conditions, when the machine has been brought to a stop to permit manipulation of the upper materials by the operator preparatory to continuing the operative movements of the wipers, to impart a short retractive movement to the wipers so as to relax their pressure on the shoe and thus permit the upper materials to be manipulated more readily. For this purpose there is provided a hand lever 146 (Fig. 1) which is pivoted at one end upon a bracket 148 on the frame of the machine and is positively connected between its opposite ends by means of a link 150 to the wiper carrier 22. The hand lever 146 is thus arranged to act directly upon the wiper carrier 22 to move it toward the left (Fig. 1), at the same time swinging the lever 26 and thereby, through the mechanism connected to this lever, imparting retractive movement to the wiper-closing plunger 62 and upward movement to the operating rod 50 against the resistance of its spring 53. The wipers are thus retracted bodily in a direction lengthwise of the shoe and are at the same time moved apart to relax their pressure on the sides of the toe. A time in the cycle when it may be useful thus to back off the wipers to permit manipulation of the upper materials is when the wipers are beginning to wipe the upper inwardly from the edge of the insole. At this time the spring 53 in the wiper-operating connections will not be under any substantial compression from movement of the coupling member 52 relatively to the rod 50 and there will accordingly be sufficient space between the bearing 76 and the nuts 78 to permit the wipers to be backed off as far as required.

In the appended claims the expression "indeterminate point" is used with reference to the cycle of operations to signify a stopping point not predetermined by the structure of the machine.

Having described the invention, what I claim as new and desire to secure by Letters Patent of the United States is:

1. In a machine of the class described, the combination with a shoe support, end-lasting wipers, and power-driven means comprising a clutch movable in one direction to effect relative movements of said shoe support and wipers in a definite cycle to last an end of a shoe, and then to return the parts of the machine to starting positions, of power-operated means for stopping the machine at a definite point prior to the end of its cycle, and manu-

ally operable controlling means enabling the operator also to stop the machine at will at an indeterminate point in its cycle.

2. In a machine of the class described, the combination with a shoe support, end-lasting wipers, and power-driven means for effecting relative movements of said shoe support and wipers in a definite cycle to last an end of a shoe by wiping the upper inwardly over the bottom of the last, of controlling means comprising a manually operated member movable to start the machine and reversely movable into position to stop the machine at any point in its cycle, and automatic means for stopping the machine at a definite point in its cycle if said member is not moved into stopping position.

3. In a machine of the class described, the combination with a shoe support, end-lasting wipers, and power-driven means comprising a clutch movable in one direction to effect relative movements of said shoe support and wipers in a definite cycle to last an end of a shoe and then to return the parts of the machine to starting positions, of a treadle depressible to start the machine, controlling mechanism operated by said treadle and constructed to cause the machine to come to a stop immediately upon release of the treadle, and automatic means for moving said controlling mechanism into position to stop the machine at a definite point prior to the end of the cycle if the treadle is not released.

4. In a machine of the class described, the combination with a shoe support, end-lasting wipers, and power-driven means including a clutch movable in one direction to effect relative movements of said shoe support and wipers in a definite cycle to last an end of a shoe and then to return the parts of the machine to starting positions, of a clutch-controlling member and a treadle connected to said member for moving an element of the clutch into operative position and for holding it in that position to cause the machine to run under power, and power-operated means for moving said member reversely to stop the machine at a definite point prior to the end of the cycle if the treadle is not released.

5. In a machine of the class described, the combination with a shoe support, end-lasting wipers, and power-driven means including a clutch for effecting relative movements of said shoe support and wipers in a definite cycle to last an end of a shoe, of a clutch-controlling member, a lever connected to said member, a manually operated member for swinging said lever to start the machine, and automatic means for swinging said lever about a different fulcrum to stop the machine while said manually operated member is still acting on the lever.

6. In a machine of the class described, the combination with a shoe support, end-lasting wipers, and power-driven means including a

clutch for effecting relative movements of said shoe support and wipers in a definite cycle to last an end of a shoe, of a clutch-controlling member, a lever connected to said member, a treadle arranged to act on said lever to start the machine, and automatic means arranged to swing said lever about a fulcrum point at its connection with the treadle to stop the machine at a definite point in its cycle while the treadle is still acting on the lever.

7. In a machine of the class described, the combination with a shoe support, end-lasting wipers, and power-driven means including a clutch for effecting relative movements of said shoe support and wipers in a definite cycle to last an end of a shoe, of a clutch-controlling member, a lever connected at a point between its opposite ends to said member, a treadle arranged to act on one end of said lever to swing it about a fulcrum point at its other end to start the machine, and automatic means arranged to act on said other end of the lever to swing it about a fulcrum point at its treadle-connected end to stop the machine while the treadle is still acting on the lever.

8. In a machine of the class described, the combination with a shoe support, end-lasting wipers, and power-driven means including a clutch for effecting relative movements of said shoe support and wipers in a definite cycle to last an end of a shoe, of a clutch-controlling member, a cam-operated lever, an arm pivotally connected to said lever and connected also to said clutch-controlling member, a treadle arranged to act on said arm to swing it about its connection with the lever to start the machine, and a cam for operating said lever to swing the arm about its connection with the treadle to stop the machine while the treadle is still acting on the arm.

9. In a machine of the class described, the combination with a shoe support, end-lasting wipers, and power-driven means including a clutch for effecting relative movements of said shoe support and wipers in a definite cycle to last an end of a shoe, of a clutch-controlling member, a cam-operated lever, an arm pivotally connected at one end to said lever and connected between its opposite ends to said clutch-controlling member, a treadle arranged to act on the other end of said arm to swing it about its connection with the lever to start the machine, and a cam for operating said lever to swing the arm about its connection with the treadle to stop the machine while the treadle is still acting on the arm.

10. In a machine of the class described, the combination with a shoe support, end-lasting wipers, and power-driven means for effecting relative movements of said shoe support and wipers in a definite cycle to last an end of a shoe and to return the parts of the machine to their starting positions, of power-operated means for stopping the machine at a definite

point prior to the end of its cycle, and manually operable means constructed to enable the operator to stop the machine at will or to prevent the automatic stopping of the machine.

11. In a machine of the class described, the combination with a shoe support, end-lasting wipers, and power-driven means including a clutch for effecting relative movements of said shoe support and wipers in a definite cycle to last an end of a shoe and to return the parts of the machine to their starting positions, of clutch-controlling means comprising a manually operated member movable to start the machine and reversely movable into position to stop the machine at any point in its cycle, and automatic means for stopping the machine at a definite point prior to the end of its cycle if said member is not moved into stopping position, said manually operated member being operative by movement to a predetermined position to prevent the automatic stopping of the machine.

12. In a machine of the class described, the combination with a shoe support, end-lasting wipers, and power-driven means including a clutch for effecting relative movements of said shoe support and wipers in a definite cycle to last an end of a shoe, of a treadle and connections between said treadle and the clutch for starting the machine in response to depression of the treadle and for stopping the machine at any time upon reverse movement of the treadle, and automatic means for stopping the machine at a definite point in its cycle if the treadle is not moved into stopping position, said connections being operative in response to depression of the treadle to a predetermined position to prevent the automatic stopping of the machine.

13. In a machine of the class described, the combination with a shoe support, end-lasting wipers, and power-driven means including a clutch for effecting relative movements of said shoe support and wipers in a definite cycle to last an end of a shoe, of clutch-controlling means comprising a manually operated member movable to different positions to cause movement of the clutch in the same direction to drive the machine under power and reversely movable from either of said positions to stop the machine at will, and automatic means operative only when the member is in one of said positions to stop the machine at a definite point in the cycle.

14. In a machine of the class described, the combination with a shoe support, end-lasting wipers, and power-driven means including a clutch for effecting relative movements of said shoe support and wipers in a definite cycle to last an end of a shoe, of clutch-controlling means comprising a manually operated member and connections between said member and the clutch for moving an element of the clutch into operative position and for

holding it in that position to cause the machine to run under power, and automatic means arranged to act through said connections to stop the machine at a definite point

5 in its cycle if said member is in a predetermined position, said connections comprising parts relatively movable against yielding resistance sufficiently to prevent the automatic stopping of the machine if the manually operated member is moved beyond a predetermined position.

15. In a machine of the class described, the combination with a shoe support, end-lasting wipers, and power-driven means including a clutch for effecting relative movements of said shoe support and wipers in a definite cycle to last an end of a shoe, of clutch-controlling means comprising a manually operated member movable to start the machine and reversely movable to stop the machine at will, power-operated means for stopping the machine at a definite point in the cycle if the manually operated member is in a predetermined position, means for preventing the automatic stopping of the machine if the member is moved beyond said predetermined position.

30 16. In a machine of the class described, the combination with a shoe support, end-lasting wipers, and power-driven means for effecting relative movements of said shoe support and wiper in a definite cycle to last an end of a shoe and to return the parts to starting position, of means for bringing the machine to a stop at the will of the operator before it completes its cycle, and means enabling the operator to effect manually a reverse relative movement of the shoe support and the wipers after the machine has come to a stop.

45 17. In a machine of the class described, the combination with a shoe support, end-lasting wipers, and power means including a clutch for effecting relative movements of said shoe support and wipers in a definite cycle to last an end of a shoe, of manually operated means for controlling said clutch to bring the machine to a stop at a point in its cycle variably determined by the operator, and manually operated means for effecting reverse relative movement of said shoe support and wipers independently of the power-driving means after the machine has thus been brought to a stop.

50 18. In a machine of the class described, the combination with a shoe support, end-lasting wipers, and power-driven means for operating said wipers in a definite cycle to last an end of a shoe and to retract them from the shoe, of means for bringing the machine to a stop before it completes its cycle, and manual means positively connected to the wipers for retracting them from the shoe both length-

wise and laterally thereof sufficiently to facilitate manipulation of the upper materials after the machine has thus been brought to a stop.

19. In a machine of the class described, the combination with a shoe support, end-lasting wipers, and power means for operating said wipers in a definite cycle to last an end of a shoe and to return them to starting position, of treadle-controlled means for bringing the machine to a stop at a point in its cycle variably determined by the operator, and a hand lever connected to the wipers to enable the operator to retract them from the shoe independently of the power-driving means after the machine has thus been brought to a stop.

20. In a machine of the class described, the combination with a shoe support, end-lasting wipers, and power-driven means including a clutch for operating said wipers in a definite cycle to last an end of a shoe, of means for bringing the machine to a stop before it completes its cycle, and manually operated means for imparting to the wipers positively retractive movement lengthwise of the shoe and opening movement sufficient to facilitate manipulation of the upper materials after the machine has thus been brought to a stop.

25 21. In a machine of the class described, the combination with a shoe support, end-lasting wipers, and power-operated means including a yielding element for advancing and closing the wipers to last an end of a shoe, of means for bringing the machine to a stop prior to the completion of the lasting operation, and manually-operated means for imparting to the wipers retractive movement against the resistance of said yielding element after the machine has thus been brought to a stop.

35 22. In a machine of the class described, the combination with a shoe support, of end-lasting wipers, a wiper carrier movable to advance the wipers lengthwise of the shoe, connections for simultaneously closing the wipers as they are advanced, power-operated means including a yielding element for advancing the wiper carrier and operating said connections, controlling means for bringing the machine to a stop prior to the completion of the lasting operation, and a manually-operated member connected to said wiper carrier for retracting it and for simultaneously imparting retractive movement to the wiper closing connections against the resistance of said yielding element after the machine has thus been brought to a stop.

40 23. In a machine of the class described, the combination with a shoe support, end-lasting wipers and power-driven means comprising a clutch movable in one direction to effect relative movements of said shoe support and wipers in a definite cycle to last an end of a

shoe and to return the parts of the machine to starting positions, of controlling means for bringing the machine to a stop at the will of the operator at an indeterminate point in the cycle, and means arranged to be rendered operative at the will of the operator to bring the machine to a stop at an automatically determined point prior to the end of the cycle.

24. In a machine of the class described, the combination with a shoe support, end-lasting wipers and power-driven means comprising a clutch movable in one direction to effect relative movements of said shoe support and wipers in a definite cycle to last an end of a shoe and to return the parts of the machine to starting positions, of controlling means comprising a manually operated member movable either into a position to cause the machine to come to a stop at an indeterminate point in the cycle or into a position to cause it to come to a stop at an automatically determined point prior to the end of the cycle.

25. In a machine of the class described, the combination with a shoe support, end-lasting wipers and power-driven means for effecting relative movements of said shoe support and wipers in a definite cycle to up-wipe the upper of a shoe to the edge of the insole and then to wipe it inwardly over the insole, of means for bringing the machine to a stop at an automatically determined point substantially at the end of the over-wiping operation, and manually controlled means enabling the operator to bring the machine to a stop at will at an indeterminate point substantially at the end of the upwiping operation.

In testimony whereof I have signed my name to this specification.

ARTHUR F. PYM.
